(57) **CLAIM**

The ornamental design for an adhesive sticker set for shoe, as shown and described.

DESCRIPTION

FIG. 1 is a top perspective view of an adhesive sticker set for shoe showing my new design;

FIG. 2 is a bottom perspective view thereof;

FIG. 3 is a front view thereof;

FIG. 4 is a back view thereof;

FIG. 5 is a top view thereof;

FIG. 6 is a bottom view thereof;

FIG. 7 is a left view thereof;

FIG. 8 is a right view thereof; and,

FIG. 9 is a top view, showing the adhesive sticker set for shoe in an alternate, flat configuration.

The broken lines in FIG. 1-8 illustrate the environmental structure of the adhesive sticker set for shoe and form no part of the claimed design.
